UNITED STATES PATENT OFFICE.

WILLIAM H. BAKER, OF CENTRAL FALLS, RHODE ISLAND, AND FREDERIC E. KIP, OF MONTCLAIR, NEW JERSEY.

DESIGN FOR A COP-TUBE.

SPECIFICATION forming part of Design No. 31,636, dated October 10, 1899.

Application filed August 19, 1899. Serial No. 727,855. Term of patent 14 years.

To all whom it may concern:

Be it known that we, WILLIAM H. BAKER, residing at Central Falls, Providence county, Rhode Island, and FREDERIC E. KIP, residing at Montclair, Essex county, New Jersey, citizens of the United States, have invented a new and original Design for a Cop-Tube, of which the following is a specification, reference being had to the accompanying drawings, forming a part thereof.

In said drawings, Figure 1 is a perspective view of a cop-tube embodying our design, and Fig. 2 is a cross-section thereof.

The leading feature of our design consists in the elongated tubular body having in its side an aperture.

A is the elongated body of the cop-tube, and *a* is the aperture in the side thereof.

What we claim is—

The design for a cop-tube, substantially as shown and described.

In witness whereof we have hereunto signed our names, this 31st day of July, 1899, in the presence of two subscribing witnesses.

WILLIAM H. BAKER.
FREDERIC E. KIP.
